UNITED STATES PATENT OFFICE.

LEWIS FAUL, OF PEORIA, ILLINOIS, ASSIGNOR TO CLARK, QUIEN & MORSE,
A CORPORATION OF ILLINOIS.

GEARING FOR WASHING-MACHINES.

SPECIFICATION forming part of Letters Patent No. 716,017, dated December 16, 1902.

Application filed November 9, 1898. Serial No. 695,954. (No model.)

To all whom it may concern:

Be it known that I, LEWIS FAUL, a citizen of the United States, residing at Peoria, in the county of Peoria and State of Illinois, have 5 invented certain new and useful Improvements in Gearing for Washing-Machines, of which the following is a specification, reference being had therein to the accompanying drawings.

10 My invention has relation to improvements in gearing for washing-machines; and the object is to provide improved and simplified mechanism for imparting reciprocating rotary and reciprocating vertical movements to 15 the rubber block or agitator.

I have fully and clearly illustrated the invention in the accompanying drawings, wherein—

Figure 1 is a view, partly in central section 20 and partly in side elevation, showing my invention applied to a well-known construction of rubber block. Fig. 2 is an end elevation looking from the right of Fig. 1. Fig. 3 is a top plan view.

25 A designates a tub or receptacle, in which the articles to be washed are deposited. This receptacle may be of any desired size and capacity and of such shape and contour as may best suit it for the purposes intended. In the 30 cover of the tub is formed a suitable opening 1, through which access is had to the interior, and this opening is closed by a door or lid 2, closely fitted thereto and working on suitable hinges 3, substantially as shown, and 35 held closed by buttons 4 or other proper fastenings.

B designates the rubber block or agitator, which may be of any desired construction. I have shown it as composed of radial arms provided with downward-projecting arms or 40 pieces. In the center of the body of the rubber is fixed a vertical stem 5, which passes loosely through an aperture 6 in the lid of the tub and projects upward above the lid and 45 is formed with a rounded end 7 at its upper end, which round end is rotatively connected to a stirrup or frame, as hereinafter more specifically described. Secured to the door or lid of the tub is a frame C, composed of a substantial base piece or plate 8 and a cross-piece 9, arranged above the base-plate and from

which project oppositely-disposed and alining standards 10 10^X, formed on their inner faces with flanged guide-grooves 11, in which the side bars of a vertically sliding and reciprocating rectangular lifting-frame 12 engage and are held. In the lower cross-bar of the frame 12 is formed a housing 13, in the lower wall of which is formed a bearing through which the upper rounded end 7 of the stem 5 55 passes, and is secured to the frame, so that it will rotate in its bearing by means of a pin 14 or other suitable fastening. The base-plate 8 and cross-piece 9, with the standards, are held together and secured to the lid or door by 60 means of bolts 15, let through lugs or extensions on them, as indicated in Figs. 2 and 3 of the drawings. Centrally in the base-plate 8 and in the cross-piece 9 are formed seats 16 16^X, 65 having annular flanges and constituting the 70 bearings for the hub 17 of a gear wheel or pinion 18, which rotates on a horizontal plane, as shown. The hub of this wheel 18 is cored out, and in the opening thus formed the stem 5 of the rubber block is slidingly disposed, the 75 stem being held to rotate with the wheel by being made angular or provided with flanges, as indicated, interengaging with like depressions or shapes in the core of the hub. On the stem of the rubber block is arranged a 80 spiral spring 8, bearing with one end against the under side of the lid and with the other end against the head of the rubber block, the expansive force of the spring serving to assist in pushing the rubber block down after 85 being raised and also to keep the lifting-frame in contact with the cam at all times.

Secured to the lid is a bracket 19, in the bridge of which is formed a vertical bearing 20 of such length and diameter as to insure a 90 stable retention of and suitable bearing for the stud shaft or journal 21 of a bevel gear-wheel 22, which is held against downward displacement by a pin 23, the ends of which project over and lie on the end edges of the 95 bearing. On the under face of the bevel gear-wheel 22 is formed or secured a downward-projecting pin 24 in the nature of a wrist-pin and to the lower end of which is pivotally connected the one end of a rock-gear 25, which extends forward into engagement with the gear wheel or pinion 18 and 100

- is kept in such engagement by a flange 26 on the face of the base-plate 8. Formed on the bracket 19 is a vertically-extending arm 27, having a bearing 27^x formed thereon, and extending from the base-plate of the frame is an arm or support 28, having its outer portion curved or directed upward, substantially as indicated, and formed or provided with a bearing 29, the seat of which is in alinement with the bearing 27^x, and in these bearings 29 27^x is journaled the shaft 30. On the shaft 30 is mounted a bevel gear-wheel 31, which engages with the bevel gear-wheel 22 to actuate the rack-bar and impart rotation to the rubber block. On the outer end of the shaft 30 is secured a fly and power wheel 32 to equalize the movements of the mechanism and to which power is applied by means of a hand grasp or piece 33. On the inner end of the shaft 30 is formed or secured a cam 34, the head of which travels on the upper and lower bars of the lifting-frame 12 and serves to lift and depress that and in sequential effect reciprocate the rubber block.
- 25 The operation and function of the respective parts and elements have been particularly specified in the description. The full and combined operation may be here summarized as follows, to wit: Power is applied 30 to the fly or power wheel, and that being turned as desired rotation is imparted to the shaft 30 and through the agencies of the gear-wheel thereon and the bevel gear-wheel 22, connected to the rack-bar, the pinion on the stem of the rubber block is rotated and of course the rubber block carried by the stem. This rotary movement agitates and rubs the things being washed. At the same time the cam actuates the frame vertically, 40 either downward or upward, and imparts coincident movement to the rubber block. Thus the articles in the tub are continually agitated and pounded by the dual movement of the rubber block.
- 45 It will be seen that the gearing which operates the pinion 18 upon the shaft or stem of the rubber block, and thus imparts the horizontal movements or oscillations thereto, is arranged in horizontal planes—that is, in 50 planes which are parallel with the planes in which the rubber block is oscillated—and also that the gearing which imparts the up-and-down or reciprocatory movements to the rubber block operates or moves in vertical planes—that is, in planes which are parallel with the planes in which the rubber block reciprocates—and that both of these sets of gearing are operated from a common motor-shaft. What I claim is—
- 60 1. The means herein described for imparting to a shaft 5 rotative reciprocative and

vertically-reciprocating movements, comprising a vertically-reciprocating frame having upper and lower cross-bars connected to the said shaft, a pinion on the shaft, so disposed thereon as to rotate the shaft and permit longitudinal movement thereof, a rack-bar to rotate the pinion, a gear-wheel to reciprocate the rack-bar, a gear to operate the first-named gear-wheel, a shaft 30, a cam on the last-named shaft to engage the said upper and lower cross-bars of the said frame and vertically reciprocate the shaft 5, substantially as specified. 65

2. The combination of a vertical shaft, the said shaft being mounted so as to be free to oscillate and also to reciprocate in the direction of its length, a pinion mounted upon the said shaft, which is free to slide through the same, horizontally-disposed gearing for driving the pinion and imparting the oscillations to the shaft, vertically-disposed gearing for imparting to the shaft its up-and-down reciprocations, and a common motor-shaft for driving both of said sets of gearing, substantially as set forth. 70

3. The combination with a vertically-disposed shaft free to oscillate and to move in the direction of its length, a pinion 18 mounted upon said shaft, a reciprocatory rack-bar movable in a horizontal plane to engage with the pinion, gearing mounted in a vertical plane and arranged to impart reciprocations to the said shaft in the direction of its length, a motor-shaft arranged to operate the said gear, 90 and other gearing arranged between the motor-shaft and the horizontal reciprocatory rack-bar, substantially as set forth. 95

4. Gearing, comprising a vertical shaft adapted to oscillate and also reciprocate in the direction of its length, vertical standards, a rectangular frame, having upper and lower cross-bars, slidably arranged between the standards, and having the upper end of the said shaft rotatively connected thereto, a pinion on the shaft having its hub slidably disposed thereon, a rack-bar to engage the pinion and impart rotative reciprocative motion thereto, a horizontally-disposed bevel-gear, having pivotal connection to one end of the rack-bar, a horizontal shaft, a bevel-gear on the shaft to engage the horizontally-disposed bevel-gear, and a cam on the end of the shaft to engage the upper and lower bars of the said frame, substantially as specified. 100 105 110 115

In testimony whereof I affix my signature in presence of two witnesses.

LEWIS FAUL.
